J. C. McFERRAN AND A. P. BLUNT, OF WASHINGTON, DISTRICT OF COLUMBIA.

Letters Patent No. 85,947, dated January 19, 1869.

IMPROVEMENT IN WAGON-BODIES.

The Schedule referred to in these Letters Patent and making part of the same.

To all whom it may concern:

Be it known that we, J. C. McFERRAN and A. P. BLUNT, of Washington, in the county of Washington, and District of Columbia, have invented a new and valuable Improvement in Wagon-Bodies; and we do hereby declare that the following is a full, clear, and exact description of the construction and operation of the same, reference being had to the annexed drawings, making a part of this specification, and to the letters and figures of reference marked thereon.

Figure 1, of the drawings, is a side view of our wagon-body, broken off to show a hinge thereof;

Figure 2 is a view of the rear end of our wagon-body; and

Figures 3 and 4 are details.

Our invention relates to wagon-bodies; and

It consists in furnishing, for the use of an army, a wagon-body that can be folded together and readjusted by novel and efficient means, the object being to economize space in the transportation thereof.

The letter A, of the drawings, represents the bottom of our army-wagon body, and the letters B represent the sides.

The front end-board is marked *a*, and the rear end-board is marked *c*, all of which are framed or battened in such manner as to give them great strength and durability.

At the rear end of our wagon-body, and passing vertically, as shown, through the top, middle, and bottom slats of the side-boards, respectively, are the rods *b*.

These rods are riveted to the said top and bottom slats, and have threads cut upon them, immediately below said top slats, adapted to receive and work with small nuts marked *i*.

This rear end-board is adjustable between the rods last mentioned and the boards of the side-boards, by means of slots cut in said end-board, and when adjusted, is held firmly in place by means of the button *s*, arranged and operating as shown.

At the outer ends of the bottom cross-bar of the wagon-body, marked *t*, and which also serves as one of the rocking bolsters of the body, we affix the hinged braces *u*. These braces extend, respectively, from the ends of said bolster *t*, in diagonal lines, until they intersect the rods *b*, at points immediately below the top side-rails of the body. At the points last named these braces are clasped around said rods, and are held in the desired position firmly, by means of the nuts *i*,

working upon the threads of said rods, below the clasps thereof.

The front end-board of our wagon-body is constructed in two parts, and hinged together in the manner shown, and a tool-box, *v*, is attached thereto, in such manner that the front side of said box forms a part of the end-board.

The letters *w* are hinges, connecting the side-boards of the body with the bottom thereof, and furnishing means by which said side-boards may be folded inward at will, so that they may rest upon the bottom respectively. Care must be taken to construct the side-boards of sufficient width to cover the bottom, and not overlap each other. When thus folded, said side-boards form an even floor above the bottom, and serve as a firm bed to receive another folded wagon-body. Five or six bodies may thus be made to occupy no more space than one ordinary body not constructed for folding.

On the top of the side-rails of the bottom, I affix a series of spurs, marked *y* on the drawings. These spurs fit into corresponding grooves or openings in the bottom rails of the side-boards, respectively, and operate as braces and supports for the parts thus united, and especially giving strength and firmness to the hinges *w* and the hinged braces *u*.

Our device possesses great merits, not only as an aid in transportation of army-wagons by land and of shipboard, but also in various agricultural and commercial pursuits; as, for example, the farmer who is desirous of economizing room in his shed, barn, or other carriage-depository, may fold the bodies of his wagons together, and hoist them upward out of reach.

Various other economical results to be gained by the use of our folding wagon-body will readily suggest themselves to a practical mind.

What we claim as our invention, and desire to secure by Letters Patent, is—

A wagon-body, constructed in the manner herein shown and described, and having rods *b*, hinged braces *u*, nuts *i*, spurs *y*, and hinges *w*, combined, arranged, and operating substantially as specified.

In testimony that we claim the above, we have hereunto subscribed our names, in the presence of two witnesses.
